OAR LOCK

Charles O. Burr, South Norwalk, Conn.

Application May 19, 1933, Serial No. 671,843

4 Claims. (Cl. 9—26)

This invention relates to new and useful improvements in oar locks and has for an object to provide an oar lock and mounting therefor including means whereby the oar lock may be secured in place so that it will not be lost and yet may be readily detached.

Another object is to provide an oarlock including means whereby an oar will not slide out of the oar lock and be lost should the operator let go of the oar.

A further object is to provide an oar lock which is so constructed that two oars may be placed in it at the same time and clamped or locked together so that they may be easily carried.

Other objects and advantages will become apparent from a consideration of the following detailed description taken in connection with the accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:

Fig. 1 is an elevational view showing the oar lock alone;

Fig. 2 is an elevational view showing a portion of a boat with a mounting bracket secured to the gunwale and the stem of the oar lock secured in said bracket;

Fig. 3 is a horizontal sectional view taken substantially along the line 3—3 of Fig. 2;

Fig. 4 is a vertical sectional view taken substantially along the line 4—4 of Fig. 2;

Fig. 5 is a view somewhat similar to Fig. 4 but showing the locking action;

Fig. 6 is an elevational view illustrating the positioning of a pair of oars in a single oar lock in order that the oars will be secured together and more conveniently carried;

Fig. 7 is a view similar to Fig. 6 but showing the two oars in place in one oar lock;

Fig. 8 is a sectional view taken substantially along the line 8—8 of Fig. 7;

Fig. 9 is an elevational view on a reduced scale and showing two complete oars in one oarlock in position for convenient carrying in one hand; and

Fig. 10 is a perspective view illustrating the device as mounting a sculling oar.

Referring in detail to the drawings, the improved oar lock includes a body 15 substantially in the form of a fork comprising arms 16 and 17 connected at their inner ends by a bight portion 18 from which extends a mounting stem or shank

19 at the upper end of which is a washer-like portion 20 providing a bearing shoulder or surface. A laterally extending lug 21 is carried by the inner end portion of the stem 19 and the inner end portions of the arms 16 and 17 are rounded as at 22 to provide a rest and bearing surface for an oar. Outwardly of said portion 22 the arms for a distance extend in substantially parallel relation as regards their inner surfaces as at 23.

The outer ends of the arms are turned to 10 extend toward one another as at 24 providing a restricted throat or opening 25 and inner shoulders 26 the purpose of which will later appear. Connected with the body 15, as to the arm 16 thereof, is one end of a flexible connecting means 15 here shown as a chain 27. The outer end of this chain 27 is connected with a closed eye 28 formed at one end of a coil spring 29. This spring 29 has its other end portion bent to form a hook 30 adapted to be engaged with the eye 28 at certain 20 times as will be hereinafter fully set forth.

A bracket generally designated 31 is adapted to receive the stem 19 of the oar lock and mount the oar lock. This bracket is secured to the gunwale 32 of a boat a portion of which is generally 25 designated 33. Bracket 31 includes a top flange 34 and side flanges 35 through which screws 36 are passed to secure the bracket in place. Extending vertically through the body of the bracket is an opening 37 and the bracket is also provided with 30 a key-way 38 in one side of said opening 37. The stem 19 of the oar lock is mounted in said opening 37 and when inserting the stem in the opening the key-way 38 accommodates the laterally extending lug 21. Figs. 2 and 4 clearly illustrate 35 that stem 19 is of a length to extend entirely through the bracket so as to dispose the lug 21 below the lower edge of the bracket when the stem is fully in place. With the parts thus positioned the bearing portion 20 rests or bears on the upper 40 or top flange 34 of the bracket.

When the oar lock is thus assembled on the bracket the former is given a partial turn so as to carry the lug out of registry with the key-way 38 and prevent casual movement of the oarlock out of the bracket. This is the position the lock normally occupies when the oar is used for rowing. Thus the oar has to be brought to a position substantially parallel with the side of the boat in order to remove the lock from the 45 bracket. As an additional safety feature, the bracket is provided with a transverse opening 39 extending across or transversely of the keyway 38 and a pin 40, such for example as a split cotter pin, as the spring action of its individual parts 50

will frictionally retain it in the opening, is provided for insertion through this transverse opening. As will be apparent from Fig. 5 when the pin 40 is in place the oarlock may not be removed from the bracket since should the lug 21 register with the keyway 38 movement of the lug through the keyway will be prevented by the pin 40. A chain 41 or other flexible means is connected at one end to the pin and at the other end to the bracket 31 as by a ring 42.

The opening represented by the throat 25 between the outer ends of the arms of the fork is such as to permit of the passage of a blade 43 of an oar and such as to prevent the passage of a loom portion 44 of an oar. It will, therefore, be seen that when the oar lock has been secured to the bracket by the insertion of the pin 40 through the opening 39, an oar in the lock may not be lifted out of place by any casual movement or by any casual impetus which may be given to the oar and such as is likely to happen in rough water. During use it is the loom of an oar which rests on the surface 22 and since the loom portion of the oar may not be moved upwardly through the throat 25 and since the oar lock is secured to the bracket by the lug 21, and more particularly by said lug and the pin 40, it will be apparent that there is little danger of the oar getting out of place.

An oar is positioned in the lock, preferably by inserting the blade portion through the lock as suggested with the oar (A) in Fig. 6. When the oar is in place the spring 29 is wrapped about the loom of the oar and the hook 30 of said spring engaged with the eye 28 thereof as also illustrated in Fig. 6. The length of the spring 29 is such that it must be stretched or tensioned when it is secured about an oar whereby it tightly grips the same so that the oar may not slide through the spring. The spring should be fairly stiff and strong so as to firmly grip the oar and not easily slide thereon. It will, therefore, be understood that the spring gripping the oar and being secured to the oar lock by the chain or other flexible means 27, the oar and oar lock are secured together so that the oar will not be lost should the operator release it. Also, with this particular arrangement the oar lock may remain secured to the oar even when the latter is not in use as when in a boat house or the like.

From the foregoing it will be seen that when the oar lock has been secured to the bracket 31 it is impossible for the oar lock to casually become disconnected from the bracket. However, on removal of the pin 40 from the opening 49 the oar lock may be lifted out of the bracket after turning it so the lug 21 is in alignment with the key way 38. Further, the restricted throat portion 25 prevents separation of the oar and lock by vertical movement of the loom portion of the oar in the lock. An additional advantage of this particular oar lock resides in the fact that it may be used to secure two oars together so that they may be conveniently carried. This last arrangement is clearly illustrated in Figs. 6, 7, 8 and 9, the method of inserting the oars in the lock being illustrated in Fig. 6.

To secure two oars together by the lock, one oar, such as the oar (B) of Fig. 6, is positioned in the lock and then the second oar is inserted into place, the throat 25 of the lock permitting of the passage of the blade 43 of the second oar

which is designated (A). When the two oars are in place the oar (B) will be in engagement with the inner surface of the bight portion 18 of the lock while the oar (A) will be bearing against the inturned portions 24 of the lock as clearly illustrated in Fig. 8. The outer end portions of the blades of the oars will be in engagement as shown in Fig. 9 while the loom portions of the oars will be at a slight incline to one another. The two oars may then be carried in one hand by gripping one of the oars, the weight of the oars and the cramping action resulting from the holding of only one of them causes them to be tightly locked together. This will leave the other hand free for carrying other articles.

Fig. 10 illustrates the application of a bracket 31 to the stern of a boat whereby the oar lock 15 is mounted to accommodate a sculling oar 45. The structure of the bracket and oar lock of Fig. 10 does not differ from that of the other figures, the only difference residing in the fact that in Figs. 2 through 5, the device of the invention is applied to the side of a boat for rowing whereas in Fig. 10 it is applied to the stern of the boat for sculling.

Having thus set forth the nature of my invention, what I claim is:

1. In an oar lock, a body to receive the loom of an oar, a stem extending from said body to mount the same, a coiled spring to encircle and grip the loom of an oar independent of said body, and flexible means connecting said spring to said body.

2. In an oar lock, a body to receive the loom of an oar, a stem extending from said body to mount the same, a coil spring, hook means on the ends of said spring, said spring adapted to be wrapped about the loom of an oar and have its ends hooked together whereby the spring encircles and grips the oar, and flexible means connecting said spring with said body.

3. In an oar lock, a body including a pair of side arms connected at their inner ends by a bight portion and having their outer end portions extending toward one another and partially closing the space between them and providing an entrance of a width less than the diameter of the loom of an oar, said arms between the bight and inturned end portions spaced apart a distance at least equal to the diameter of the loom of an oar, and each of said arms between said portions of a length at least equal to twice the diameter of the loom of the oar whereby the loom portions of a pair of oars may be simultaneously clamped in the oar lock between its bight portion and the inturned ends of its arms.

4. In an oar lock, a body including a pair of side arms connected at their inner ends and curved to receive and hold the loom of an oar while used in rowing, said arms having substantially straight portions extended upwardly above said curved portions with their outer end portions extending inwardly toward each other and spaced apart a distance less than the diameter of the loom of an oar, and said substantially straight portion being of sufficient length for insertion of the loom of a second oar over that of an oar in the curved portion so that both oars are retained in the lock by the inwardly turned end portions, and means for mounting said lock.

CHARLES O. BURR.
